C. J. PILLIOD

VALVE GEAR

Filed Feb. 26, 1921

Patented Aug. 28, 1923.

1,465,948

UNITED STATES PATENT OFFICE.

CHARLES J. PILLIOD, OF TOLEDO, OHIO, ASSIGNOR TO DANIEL SEARLES, TRUSTEE, OF TOLEDO, OHIO.

VALVE GEAR.

Application filed February 26, 1921. Serial No. 443,142.

To all whom it may concern:

Be it known that I, CHARLES J. PILLIOD, a citizen of the United States, and a resident of Toledo, in the county of Lucas and State of Ohio, have invented a certain new and useful Valve Gear; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to valve gears and particularly to those of the link type of reverse for use on locomotives.

In a former application filed February 10, 1921, Serial No. 443,743, I have shown a link form of reverse gear of the Walscheart type changed to conform to my invention. The present invention shows a different form of reverse gear of the link type and its object is to provide such a gear with the features of my invention and also to provide a simple and compact form of valve gear of the link type of reverse which is cross-head driven and capable of use in certain connections where other types of gears could not be conveniently employed.

The invention is fully described in the following specification, and while in its broader aspect it is capable of embodiment in numerous forms, a preferred embodiment thereof is illustrated in the accompanying drawings, in which,

Figure 1 is a fragmentary side elevation of a locomotive equipped with my improved valve gear. Fig. 2 is a fragmentary top plan view of one side portion thereof. Fig. 3 is a central vertical section through the links and cross-shafts of the valve gears. Fig. 4 is a cross-section of the reverse link taken along the center line of the radius rod, with parts of the latter in full, and Figs. 5, 6, 7 and 8 are different views of two of the members forming the reverse link.

Referring to the drawings, 1 designates a locomotive frame, 2 the locomotive drive wheels, 3 an engine, one of which is located at each side of the locomotive, 4 a cross-head operated by the piston of each engine, and 5 the engine valve-stem cross-head guide.

The reversing mechanisms for the valve

gears one of which is located at each side of the locomotive, have two shafts, 6 and 7, telescoped one within the other and extending cross-wise of the locomotive with their ends suitably journaled in side brackets 8 of the locomotive frame. The outer or sleeve shaft 6 carries, in the present instance, at the right side of the locomotive a downwardly extending radius-arm 9, and at the other side of the locomotive a reverse-link 10 for rocking movements therewith. The cross-shaft 7 carries a downwardly extending radius-arm 11 at the left side of the locomotive and a reverse-link 12 at the right side thereof. Each reverse-link comprises opposed side members 13 and 14 and an interposed slotted guide plate 15, the whole being bolted or otherwise suitably secured together. The side member 13 is fixed to the respective cross-shaft and the side member 14 is provided at its outer side with a trunnion 16 in axial register with the cross-shaft and journaled in a bearing in the associated frame bracket 8.

Each reversing mechanism is provided with the customary radius-rod 17, one of which is provided at each side of the locomotive and has its forward end pivoted to the associated combination lever 18 which is fulcrumed to the valve stem cross-head of the associated engine, as well understood in the art. The lower end of the combination lever is connected by a link 19 to the associated cross-head 4. The radius-rod 17 at the right side of the locomotive extends through the link 12 and has a part which straddles and is guided for shifting movements longitudinally of the reverse link by the center guide piece 15 thereof. The radius-rod 17 at the opposite side of the locomotive projects through and is connected in the same manner to the reverse-link 10. The movements of the radius-rods 17 lengthwise of the respective reverse-links 10 and 12 to place them in neutral or in forward or reverse running positions, are accomplished by the rocking of a pair of cross control shafts 20 and 21, which are suitably mounted in the locomotive frame at the rear of the cross-shafts 6 and 7. The shaft 20, which is sleeved on the shaft 21 is provided at the right side of the locomotive with a forwardly projecting rocker-arm 22, which has wrist-pin connection with a collar 23 slidingly mounted on the rear end of the as-

sociated radius-rod 17. The shaft 21 at the left side of the locomotive is provided with a forwardly projecting arm 24, which has wrist-pin connection with a collar 25 that is 5 slidingly mounted on the radius-rod 17 at the left side of the locomotive. The cross-shafts 20 and 21 have reverse rocking movements simultaneously imparted thereto from a control plunger or rod 26, the movement 10 of which is controlled in any suitable manner. This rod is connected by a link 27 to an upwardly extending arm 28 on the sleeve shaft 20 and is connected by a link 29 to a downwardly extending arm 30 on the shaft 21. It is thus evident that a rearward movement 15 of the control rod 26 from the forward position shown in Figure 1 will raise the rocker-arm 22 and lower the rocker-arm 24 and impart corresponding movements to the two radius-rods 17 with respect to the reverse links; thereby placing the radius-rods in neutral or at desired points in reverse running positions. This manner of 20 connecting the control rod 26 with the respective radius-rods so as to impart reverse movements to the radius-rods is necessary on account of the cross-heads 4 of the two engines being set at 90° to each other.

The requisite rocking movements are imparted to the reverse links 10 and 12 during a running of the locomotive from the cross-heads 4 of the engines, the cross-head at the right side of the locomotive being connected by a link 31 to the rocker-arm 9 30 which is carried by the shaft 6 and operates the reverse-link 10, while the cross-head 4 at the left side of the locomotive is connected by a link 32 to the rocker-arm 11, which is carried by the cross-shaft 7 and operates the reverse-link 12. It is thus evident 35 that the cross-head 4 at each side imparts accelerated travel to the engine valve at the other side of the locomotive through the valve gear which is connected and operated 40

by the respective cross-head, and that the 45 lap and lead travel of each valve is received from the cross-head 4 at the same side of the locomotive therewith through the associated link 19 and combination-lever 18.

The cross connecting of a valve gear at 50 one side with the valve at the other side of the locomotive to obtain the accelerated travel of the valve is necessary in order to impart high speed travel to the valve when the actuating cross-head is at either extreme 55 of its travel. This is accomplished in drive wheel driven reverse gears by setting the connection of the reverse gear with the drive wheel 90° in advance of the main rod pin.

I wish it understood that my invention is 60 not limited to any specific construction, arrangement or form of the parts, as it is capable of embodiment in numerous forms, without departing from the spirit of the 65 claim.

Having thus described my invention, what I claim as new and desire to secure by Letters Patent, is—

In a locomotive, the combination with an engine operated cross-head at each side and 70 an engine valve at one side of the locomotive, of a cross shaft, an arm projecting downwardly from the cross shaft at one end, link means connecting the arm and cross-head, a reverse-link carried by the shaft at 75 its other end for rocking movements therewith, a floating combination lever connected to the valve and having its lower end in operating connection with the cross-head at the valve side of the locomotive, a radius-rod 80 connecting the reverse-link and combination lever for imparting accelerated travel to the valve from a rocking of the reverse-link, the radius-rod being shiftable lengthwise of the link, and means for shifting the radius-rod. 85

In testimony whereof I have hereunto signed my name to this specification.

CHARLES J. PILLIOD.
